By their Attorneys

UNITED STATES PATENT OFFICE.

JOSEPH F. SMART AND JOHN B. GRIFFIN, OF NEW BRITAIN, CONNECTICUT, ASSIGNEES
TO LANDERS, FRARY & CLARK, OF NEW BRITAIN, CONNECTICUT, A CORPORATION
OF CONNECTICUT.

PERCOLATOR.

1,251,432.

Specification of Letters Patent. Patented Dec. 25, 1917.

Application filed October 21, 1916. Serial No. 126,847.

To all whom it may concern:

Be it known that we, JOSEPH F. SMART and JOHN B. GRIFFIN, citizens of the United States, residing at New Britain, county of 5 Hartford, State of Connecticut, have invented a certain new and useful Improvement in Percolators, of which the following is a full, clear, and exact description.

Our invention relates to improvements in 10 percolators and has for its object to provide an interior element for a percolator, constructed in such a manner as to have neither screw-threaded nor soldered joints.

The following is a description of an embodiment of our invention, reference being had to the accompanying drawings, in 15 which,

Figure 1 is a vertical section of an interior percolator-element embodying our invention.

Fig. 2 is a side elevation of the tube at one stage of its manufacture;

Fig. 3 is a plan view of the same;

Fig. 4 is a side elevation of said tube at 25 a subsequent stage of its manufacture with a clamping plate added thereto;

Fig. 5 is a plan view and side elevation of a second clamping plate;

Fig. 6 is a plan view and side elevation 30 of the clamping plate of Fig. 4;

Fig. 7 is a plan view of the base member;

Fig. 8 is an enlarged sectional view on the line 8—8, Fig. 1; and

Fig. 9 is an enlarged view partly in section on the line 9—9, Fig. 4.

Referring more particularly to the drawing (Fig. 1), 1 is a tubular member having at its bottom a swaged projection 2, having an angular contour as shown in Figs. 2, 3 40 and 4 and having also swaged projections 3 and 4 as shown in Figs. 1 and 4, between which is held a supporting plate 5 having a rectangular opening 6 as shown in Fig. 6. The swaging of the metal to form the projections 3 and 4 causes the metal to flow more or less into the angles of the rectangular opening 6. 7 is a bottom member forming a cover for producing a steam chamber, said bottom member being provided at its 45 top with a rectangular opening or recess 8, in which fits the projection 2 of the tube 1. The lower end of the tube 1 when in the condition shown in Fig. 4, is inserted into the upper end of the member 7 so that the

rectangular portion 2 lies in the rectangular 55 opening 8 and the extreme lower end of the tube 1 is then swaged or spun as shown at 9, Fig. 1, so as to be expanded and hold the member 7 upon the tube 1.

10 is the cup for holding the coffee, the 60 same being perforated on its sides and bottom in the ordinary manner. The bottom of this cup engages the plate 5 and is provided with three equidistant perforations 11. One of the plates 5 and 13 is provided 65 with means for securing the cup 10 to the other plate, said means consisting of rivet-like projections which pass through the perforations 11 and over so as to hold the cup in place. In the construction illustrated, 70 these rivet-like projections are carried by the plate 13 and are bent over as shown in Fig. 1 so as to have their lower ends engage the lower surface of the plate 5 and securely clamp the bottom of the cup 10 thereto. The 75 other plate 5 is shown as provided with spaced recesses 14 to receive the projections 12.

The rivet-like projections constituting the means for securing the cup to the plate 5 are 80 preferably integral with one of the plates 5 and 13, and the plate 13 is preferably used so that the plates 5 and 13 are both clamping plates holding the bottom of the cup between them.

The plate 5 is securely fastened to the tube, and, the lower surface of the cup 10 resting thereon, its weight is supported independently of the bent projections 12, this arrangement being the preferred construction. The angles on the tube and the angular openings in the first clamping plate and bottom element render the engaging surfaces at those points so irregular as to prevent the turning of the clamping plate, cup and bottom member upon the tube, so that by the means described all the members of the interior element are securely and rigidly fastened together without the use of screw-threads and without the use of solder.

As will be evident to those skilled in the art, our invention permits of various modifications without departing from the spirit thereof or the scope of the appended claims.

What we claim is:

1. In a percolator element, the combination of a tube having a projection thereon, a clamping plate mounted upon said tube

- adjacent to said projection, a second clamping plate mounted on said tube and located on the side of said first clamping plate adjacent to said projection so that said projection lies between said plates, and a cup having its bottom portion between said plates, one of said plates having projections engaging the side of the other plate remote from said bottom portion.
- 10 2. In a percolator element, the combination of a tube having a projection thereon, a clamping plate mounted upon said tube adjacent to said projection, a second clamping plate mounted on said tube and located on the side of said first clamping plate adjacent to said projection so that said projection lies between said plates, and a cup having its bottom portion between said plates, one of said plates having projections engaging the side of the other plate remote from said bottom portion, said tube having a second projection, and said first clamping plate

lying between and engaging both of the said projections of said tube.

3. A percolator element comprising a tube 25 having two adjacent flanges thereon, a perforated plate held between and engaging said flanges, a cup having its bottom adjacent to said plate and provided with a central opening and with openings surrounding said central opening, and means passing through said surrounding openings in said bottom for holding it to said plate.

4. A percolator element comprising a tube having two adjacent flanges thereon, a perforated plate held between said flanges, a cup having its bottom adjacent to said plate, and means passing through openings in said bottom for holding it to said plate, the opening for the tube in said plate and the tube at 40 the point between said flanges being irregular so as to prevent relative turning.

JOSEPH F. SMART.
JOHN B. GRIFFIN.
